Primary Examiner — Barbara Fox*Assistant Examiner* — Alyse Joseph(74) *Attorney, Agent, or Firm* — Slater Matsil, LLP(57) **CLAIM**

The ornamental design for a display screen or portion thereof with graphical user interface, as shown and described.

DESCRIPTION

The lone FIGURE is a front view of a display screen or portion thereof with graphical user interface for our new design.

The broken line showing of a portion of the display screen is for the purpose of illustrating environmental structure and forms no part of the claimed design.

1 Claim, 1 Drawing Sheet(56)
